(Model.)

J. R. HEBERT.

TUCK MARKING ATTACHMENT FOR SEWING MACHINES.

No. 451,869.

Patented May 5, 1891.

UNITED STATES PATENT OFFICE.

JOSEPH R. HEBERT, OF BROOKLYN, NEW YORK, ASSIGNOR TO THE DOMESTIC SEWING MACHINE COMPANY, OF OHIO.

TUCK-MARKING ATTACHMENT FOR SEWING-MACHINES.

SPECIFICATION forming part of Letters Patent No. 451,869, dated May 5, 1891.

Application filed March 8, 1886. Serial No. 194,405. (Model.)

To all whom it may concern:

Be it known that I, JOSEPH R. HEBERT, a citizen of the United States, residing in the city of Brooklyn, Kings county, and State of New York, have invented certain new and useful Improvements in Tuck-Marking Attachments for Sewing-Machines, of which the following is a specification.

My invention relates to tuck-marking attachments for sewing-machines of the class provided with notch and point, gages, and graduated scales; and it consists in the construction and arrangement of the several parts forming the attachment, whereby the several operative parts may be adjusted as a whole in their relation to the needle-bar, and also each have a separate and independent adjustment in their relation to each other.

It also consists in the means for adjustably holding the operating-lever out of operative position for engagement with the needle-bar and in other details of construction, as will hereinafter be set forth in detail, and pointed out in the claims.

Referring to the drawings, Figure 1 represents a top view of my improved tuck-marker. Fig. 2 represents an end sectional view cut through on the line xx , Fig. 1, and Fig. 3 represents a side view showing the base-plate 30 and slide in section cut through at yy , Fig. 1. Figs. 4, 5, 6, 7, 8, and 9 represent detached parts.

In the drawings, A represents an attaching-plate adapted to be held within a groove, with which the cloth-plate of the sewing-machine is usually provided, within which a removable covering-slide is usually held, which serves as a cover over part of the shuttle-raceway.

B represents a plate located above and supported by a vertically-pivoted connecting-plate D, pivoted to the attaching-plate A. A detached plan view of the plate B is very clearly represented in Fig. 5 of the drawings.

This plate B is provided with a projection or an upturned flange, which I term an "ear," (more clearly shown in Figs. 1 and 3 of the drawings,) and to which one end of a lever or arm is secured, the opposite end of which is provided with a grooved circular device adjustably attached, the adjustability being for

the purpose of changing the position of the circular groove in its relation to the engaging-surface, with which it contacts in operating when undue wear appears. In the present instance a single screw (shown at a') serves as the means for adjusting the parts, although other means might be employed to hold the parts in a desired position, as it is the adjustability of the parts in their relation to each other in the combination described that I claim (among other things) as new. The plate B also has a flexible spring attached thereto, (see Fig. 5,) with its surface toward the supporting part slightly rounded. This device serves as a sort of presser and smoother for the fabric passing beneath.

A top view of the device is very clearly represented in Figs. 1 and 5 of the drawings, while edge views may be seen in Fig. 3.

Interposed between the plates B and D already described is another one, (represented at C,) a detached view of which is shown in Fig. 6 of the drawings. This plate is provided with a vertical and an overhanging projection, these two parts serving as a guide for the edge of the material while being fed along, and also to confine between them the slide-plate B, which carries the marker, the overhanging part of one of the guides referred to serving to keep the strips from riding over the tops of the vertical parts when the attachment is in operation. A third vertical projection or flange, formed by upturning a portion of the said plate C, is located at or near the rear end of the said plate, which serves as a means for moving the guide by the hand to and from the marking-points, thereby defining the distance of the mark from the tuck which is being operated upon. The plate C, together with all of the parts above A and D, is held in position by the thumb-screw g .

The drawings at D represent another plate (more clearly shown in Fig. 7) as detached from its connecting parts, forming a kind of pivoted chair, upon which the other principal operating devices are supported upon the main plate A, previously referred to. This plate D is pivotally attached to the main plate A by screw or rivet, thus allowing it, with its connecting parts, to be swung in a horizontal

plane in and out of position at right angles or parallel, as shown by dotted lines in Fig. 1 of the drawings, for a greater convenience of boxing and condensing the same when not in use. An end view of this plate or chair D is represented in Fig. 8, showing the pivot-pin at D', and a loop-guide h, which serves to support a spring-presser similar to the one carried by the plate B, before described, while 10 g represents a screw for a thumb-nut which secures the several parts together. The sliding plates and gages are confined by a sort of covering-plate. (Shown at E in the drawings.) A detached enlarged view thereof is 15 shown in Fig. 9 of the drawings. This plate is provided with an opening for the passage of the fastening-screw and a slit serving to intersect with the loop h, before referred to, to assist in maintaining it in the proper position. The actuating-lever is also attached to 20 this plate, together with a catch-spring for holding the said actuating-lever upright, or nearly so, when not required to be used.

By the construction and combination of 25 parts described I am enabled to produce an attachment that is not only adjustable in all desirable ways for effective operation, but all parts except plates A and D are detachably held by a single screw alone. The actuating-lever for operating the marking-arm is 30 represented in Fig. 4 as detached from its connecting parts and in Fig. 2 connected and in position to receive the contact of the needle-bar, by which it is moved. The dotted lines show the position of the lever when held 35 in a vertical position when desirable for non-operation. The notches on its periphery are entered by suitable spring. The grooved wheel is adjustably held upon the arm, which 40 is vibrated by contact of the needle-bar upon the operating-lever and its position changed whenever it becomes worn from use. In this way the parts for marking may be kept in 45 proper working condition by the operator.

45 The operation of the attachment is so similar to those in general use that a detailed explanation would seem superfluous.

Having thus set forth my invention, what I 50 claim as new, and desire to secure by Letters Patent of the United States, is—

1. The combination, in a tuck-marker, of the main supporting and holding plate, the plate D, vertically pivoted thereon to horizontally rotate, two independently-adjustable 55 plates sliding upon said vertically-pivoted plate and carrying the marking apparatus

and gage, respectively, and means for adjustably holding said sliding plates and marking apparatus and gage carried thereby in their relations to each other upon said rotatable 60 vertically-pivoted plate, substantially as and for the purpose set forth.

2. In a tuck-marker, the combination, with a base-plate and a supporting-plate vertically pivoted thereon to be rotated in a horizontal 65 plane, of an independent operating-gage, a slide provided with a creasing-blade, a marker, and a smoother, and means for adjustably holding said gage and slide upon the said vertically-pivoted supporting-plate, substantially 70 as and for the purpose set forth.

3. The combination, in a tuck-marker, with the plate A and a supporting-plate vertically pivoted thereon, of an adjustable sliding plate supported on said vertically-pivoted supporting-plate, carrying a grooved wheel and creasing-rib, substantially as and for the purpose 75 set forth.

4. The combination, in a tuck-marker, of a main supporting-plate, the plate D, vertically 80 pivoted thereon, two independently-adjustable plates supported on said vertically-pivoted plate carrying the gage and marking apparatus, respectively, and a thumb-screw for holding said adjustable plates and marking apparatus 85 and gage supported thereby adjustable in their relation to each other, substantially as described, and for the purpose set forth.

5. The combination, in a tuck-marker, of a base-plate, a supporting-plate vertically pivoted 90 on said base-plate, a sliding gage and a sliding plate carrying the marking apparatus supported on said vertically-pivoted supporting-plate, and a covering-plate and screw to engage with and hold said sliding gage and 95 the sliding plate carrying the marking apparatus adjustable in their relation to each other, substantially as and for the purpose set forth.

6. The combination, in a tuck-marker, of a 100 supporting-plate, the marking apparatus and gage supported thereon, means for holding said marking apparatus and gage on the said supporting-plate, an actuating-lever provided with notches, and a spring for engaging said 105 notches to hold the lever out of operative position, substantially as and for the purpose set forth.

JOSEPH R. HEBERT.
